SPARK PLUG

Milton Beckett, Bridgeton, N. J.

Application May 4, 1939, Serial No. 271,788

1 Claim. (Cl. 123—169)

This invention relates to spark plugs, one of the objects being to provide a removable member carrying the points of the device so that these can be renewed readily without loss of the remaining portions of the spark plug.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawing the preferred form of the invention has been shown.

In said drawing:

Figure 1 is a view partly in section and partly in elevation showing the present improvements.

Figure 2 is a similar view in which the sectional core is shown mainly in section.

Figure 3 is an end elevation.

Referring to the figures by characters of reference, 1 designates the body of the plug having one end reduced and screw threaded as at 2 while its other end is provided with a counterbore 3 having a screw threaded wall 4 and an inner annular shoulder 5.

The core of the spark plug is formed of an outer section 6 and an inner section 7. The inner section includes a metal bushing 8 having slits 9 extending thereinto from one end while its other end has an annular flange 10 so shaped and proportioned as to fit snugly on shoulder 5 while the bushing is seated firmly in the reduced end portion 2 of the plug. A core section 11 of porcelain or the like is fitted securely in the bushing and carries a central electrode 12 both ends of which are exposed beyond the respective ends of the core 11 while one of said ends, 13, constitutes one of the points of the spark plug. The other point 14 is made integral with the bushing 8 and is extended close to point 13 so as to provide the necessary spark gap.

Core section 6 is of porcelain or the like and

is insertable into counterbore 3 where an annular rib 15 seats on the flange 10 and serves to clamp it firmly onto shoulder 5. A conductor 16 is extended through the core section 6 and is adapted to bear at one end against electrode 12 while its other end is exposed for connection with the ignition circuit.

A threaded sleeve 17 extends snugly around core section 6 and is insertable into the counterbore 3 where it is adapted to engage the threads 4 so as to hold section 6 tightly in place.

Should the points become burned or require removal for any other reason, it is necessary solely to unscrew sleeve 17. Core section 6 can then be lifted from plug 1 after which section 15 7 can be pushed out of the plug 1 and another section substituted. Section 6 and sleeve 17 are then replaced and the spark plug is again ready for use.

The slits 9 permit free relative expansion of 20 the porcelain section 11 and the bushing 8, when heated.

What is claimed is:

A spark plug including a body having a counterbore extending into one end and terminating at an annular shoulder, a core section including a bushing removably seated in the body and having slits extending thereinto from one end, a flange on the bushing removably seated on the shoulder, an insulator seated in the bushing and having flat ends, an electrode anchored in the insulator and projecting therefrom at its ends, one end constituting a point, a point extending from the bushing, a second section of insulating material removably seated in the counterbore and having a flat end overlying the bushing and the insulator therein, adjustable means engaging the body for holding said section seated upon the flange to clamp said flange on the shoulder, and a conductor extending through said second section and exposed at one end for contact with one end of said electrode at a point between the ends of the two insulating sections.
